UNITED STATES PATENT OFFICE.

ALMON E. NORRIS, OF CAMBRIDGE, MASSACHUSETTS.

CONTROLLING DEVICE FOR PRESSURE-FLUID ENGINES.

972,218.

Specification of Letters Patent. Patented Oct. 11, 1910.

Original application filed January 18, 1908, Serial No. 411,466. Divided and this application filed February 10, 1909. Serial No. 477,060.

To all whom it may concern:

Be it known that I, ALMON E. NORRIS, a citizen of the United States, residing at Cambridge, in the county of Middlesex and State of Massachusetts, have invented an Improvement in Controlling Devices for Pressure-Fluid Engines, of which the following description, in connection with the accompanying drawings, is a specification, like letters on the drawings representing like parts.

My invention relates to controlling devices for pressure fluid engines, the same being shown as embodied in the form of a steam engine throttle valve.

The present application, as to certain features, is a division of my prior application, Serial No. 411,466, filed January 18, 1908.

My invention will be best understood by reference to the following description when taken in connection with the accompanying drawings showing one specific embodiment thereof, while its scope will be more particularly pointed out in the appended claims.

In the drawings: Figure 1 is a central, sectional elevation showing a throttle valve embodying one form of my invention; Fig. 2 is a similar view showing the throttle valve in a different position from that shown in Fig. 1; Fig. 3 is a sectional detail in plan on the line 3—3 in Fig. 1; Fig. 4 is a sectional detail in plan on the line 4—4 in Fig. 1; and Fig. 5 is a diagrammatic view in elevation showing the application of the described form of throttle valve to a steam engine.

Referring to the embodiment of my invention shown in the drawings and first more particularly to Fig. 5, I have there shown conventionally a steam engine having the cylinder 1 to which leads the supply pipe 2, in which is interposed the throttle valve 3. If an ordinary throttle valve were employed, as soon as steam were shut off from the engine cylinder a certain amount of pressure fluid would be trapped and remain in the cylinder. Such would be apt to cause a creeping or continuation of the engine movement if the throttle were closed to stop the engine, due to the expansion of the trapped pressure fluid within the cylinder, or if it were desired to allow the driven member to turn the engine backward, it would act to prevent such free backward movement. For certain classes of work this engine creeping movement after the pressure supply has been

shut off is undesirable, and, in many cases, as for example with hoisting machinery, it is desirable to allow the load to turn the engine backward without disconnecting the same therefrom. I have herein associated with the engine a throttle valve of improved construction and such that, when closed, it not only shuts off the pressure supply from the cylinder but relieves the pressure within the cylinder by opening the latter to the exhaust sufficiently to clear the cylinder of the trapped pressure fluid, rendering the engine ineffective for moving the driven part and leaving it free to be driven backward by the driven member or load. In the form herein shown such throttle valve consists of the main body or casing 4 having an interior chamber adapted to receive the sliding throttle valve member 5.

The supply pipe 6 (Fig. 5) is connected to the supply or entrance opening 7 of the valve casing, which latter opens into an annular chamber 8, the latter having the supply port 9 controlled by the lower edge or wall of the valve member 5. When the valve member is lifted to the position shown in Fig. 2, steam can pass from the supply chamber 8 through the port 9 to the lower part of the valve chamber, whence it passes through the connecting passage 10 to the exit opening 11 of the valve casing and thence, through the supply pipe 2, to the engine cylinder.

In order to connect the engine cylinder with the exhaust, when the valve is closed, the valve member is constructed in the form of a hollow cylinder through which the lower end of the valve chamber, and hence the exit passage 11, may be connected with an annular exhaust chamber 12, the latter surrounding the valve member 5 near its upper end, such exhaust chamber having connection, through the exhaust opening 13, with the exhaust pipe 14 (see Fig. 5). Referring more particularly to the detailed construction of the valve member, the cylindrical shell of the latter is stiffened both at the top and the bottom by four radial webs 15, the cylindrical walls of the shell being also strengthened by four longitudinal ribs 16 which extend lengthwise the shell on the inside thereof and connecting the ends of the web 15. The shell is surmounted by the arched piece 17 suitably attached to the stem 18 and of such dimensions that it readily passes within the contracted opening 19 in

the end of the valve chamber, such opening, however (as shown in Fig. 2), closely fitting the valve shell when the latter is lifted.

The upper end of the valve casing is closed by a suitable cap 20 carrying the packing gland 21, through which passes the valve stem 18. The end of the stem is provided with the eye 22 to which may be secured any suitable form of valve-actuating device, there being preferably provided the collar 23 adjustably fixed on the stem and abutting against the compression spring 24, the opposite end of which latter abuts against the fixed yoke or plate 25 secured to the upright rods 26 which are secured to the cap 20. The spring, therefore, normally acts to close the valve, moving the same to the position shown in Fig. 1 where the nut 27, pinned to the stem 18, is seated against the fixed plate 25. With the valve depressed as shown in Fig. 1 admission of steam is cut off from the lower end of the valve chamber by reason of the closure of the admission port 9 while, at the same time, the exhaust chamber 12 is opened to the interior of the valve and thereby to the pipe 2 and the cylinder space by reason of the depression of the upper wall or edge of the shell below the contracted chamber opening 19. The trapped pressure fluid in the cylinder, therefore, readily passes out from the cylinder through the pipe 2, admission opening 11, passage 10, to the valve chamber, and from the valve chamber through the interior of the shell to the exhaust chamber about the upper edge of the valve, as represented by the arrows in Fig. 1. When the stem is moved up to lift the valve to the position represented in Fig. 2, the exhaust chamber is cut off from communication with the interior of the valve by the entrance of the upper edge or wall of the shell within the contracted wall portion 19.

It is to be observed that the upper end of the valve chamber within the cap 20 is at all times in free communication with the lower end of the valve chamber through the hollow interior of the valve whether the latter be positioned as in Fig. 1 to connect the interior of the valve with the exhaust, or positioned as in Fig. 2 to connect the valve interior with the pressure supply.

In order to give a gradual initial admission, the lower edge of the valve is cut back or notched, as shown, to form wide angled V-shaped openings 28. In order also to give more instantaneous release to the trapped pressure in the engine cylinder, preferably, though not necessarily, the valve is so connected as to effect, when closed, a double connection with the exhaust. For this purpose herein the shell of the valve is provided with an intermediate port 29, herein in the form of a circumferential groove cut entirely through the walls of the shell except

at the four ribs 16, which latter, in the vicinity of the port 29, are thickened as shown to strengthen the shell at that point.

In the depressed position of the valve represented in Fig. 1 pressure fluid is permitted freely to pass out from the interior of the valve to the exhaust chamber 12 through the port 29, thereby acting to supplement the exhaust which is effected about the upper edge of the valve and acting therefore instantaneously to relieve the pressure trapped within the cylinder and maintain the latter open to the atmosphere. In the upper position of the valve (Fig. 2), the port 29 is cut off from communication with the exhaust chamber by entrance into a closely fitting opening provided in a wall portion 30 projecting laterally from the valve casing into the exhaust chamber 12.

Opposite ends of the valve chamber being in communication at all times, the valve remains in an approximately balanced condition. In order to render the valve completely balanced there is provided the stem portion 31 projecting downwardly from the valve member and secured centrally thereto at the junction point of the radial webs 15. The stem 31 passes through a closely fitting opening in the lower wall 32 of the valve chamber, where its end is exposed to the pressure within the balancing chamber 33, which latter, however, is connected by the passage 34 with the exhaust chamber 12 and the exhaust pipe 14. The cross-sectional area of the stem 31 being substantially the same as that of the main valve stem 18, the valve member remains at all times in a condition of balanced pressure.

While I have herein shown and described one specific form of my invention and one specific application thereof for the purposes of illustrating it in concrete form, it is to be understood that the invention is not limited to the details of construction or the specific relation or arrangement of parts, but that extensive deviations may be made from the form described herein contained without departing from the spirit of the invention.

Having thus described one form of my invention, what I claim is:

1. The combination with a pressure fluid engine, of a controlling device therefor having means for connecting said engine with or disconnecting the same from a source of pressure fluid and also means for simultaneously connecting the said engine with the exhaust at the time of its disconnection from the pressure fluid supply, thereby to relieve the engine of the pressure fluid trapped therein.

2. The combination with a pressure fluid engine, of an engine throttle valve connected in the supply pipe therefor, said valve having means for relieving the pres-

sure trapped in said engine when said throttle valve is closed.

3. A throttle valve provided with a valve chamber, a hollow cylindrical valve member 5 adapted to move therein, a cylinder admission opening communicating with one end of said valve and adapted to be placed in communication with a pressure fluid supply chamber when said valve is moved axially, 10 and an exhaust opening adapted to be placed in communication with the opposite end of the valve when the latter is moved to a closed position.

4. A throttle valve having a valve chamber, a hollow valve, an exhaust chamber, a 15 pressure supply chamber and a cylinder chamber, said valve being connected to open communication between the cylinder chamber and the exhaust chamber about one edge 20 of the valve, when in one position, while cutting off communication between the cylinder chamber and the pressure supply chamber, and, in another position, to open the cylinder chamber to the pressure supply 25 chamber about the opposite edge of the valve, while cutting off communication between the cylinder chamber and the exhaust chamber.

5. A throttle valve having a valve member 30 provided with a cut-off wall for cutting off a suitable pressure fluid supply chamber from, or opening the same to, the valve chamber, and provided also with a plurality of cut-off walls for simultaneously opening 35 the valve chamber to the exhaust or cutting off the same from communication therewith.

6. A throttle valve having a valve cham-

ber, a hollow cylindrical valve member adapted to slide therein, the opposite ends of the valve chamber being in free communication through the hollow interior of the valve, and the valve chamber being in communication with the supply pipe of the engine or other apparatus in connection with which said valve is employed, an exhaust 40 chamber adapted in one position of the valve to be opened to the valve chamber about one edge of the valve, and a pressure fluid supply chamber adapted in another position of the valve to be opened to said 45 valve chamber about the opposite edge of the valve.

7. A throttle valve comprising a valve member adapted to be moved to shut off the supply of pressure fluid from the supply 50 opening of the valve, and simultaneously to connect the same with the exhaust, and pressure balancing means for said valve.

8. The combination with a pressure fluid engine having a supply pipe of controlling 55 means therefor in the supply pipe, the same comprising a single movable controlling member for simultaneously connecting the engine with the exhaust and disconnecting the engine from the pressure fluid supply or 60 vice versa.

In testimony whereof, I have signed my name to this specification, in the presence of two subscribing witnesses.

ALMON E. NORRIS.
